CATHODE FOR ELECTRON DISCHARGE
DEVICESAlbert W. Hull, Schenectady, N. Y., assignor to
General Electric Company, a corporation of
New York

Application October 22, 1936, Serial No. 106,999

10 Claims. (Cl. 250—27.5)

The present invention relates to electrical discharge devices and in particular to the cathode structure of such devices.

In tubes of the power type, it is customary to employ multi-cellular thermionic cathodes which are constructed to provide a plurality of cavities open to the exterior and having an internal electron-emitting surface which is of a large area compared to the volume of the cathode. In cathodes of this sort, it is also customary to employ one or more heat shields in order to reduce the thermal losses, so as to maintain the cathodes at an operating temperature with energy which is only a small fraction of the energy required, for equal electron-emitting area, with ordinary cathode structures such as are commonly employed in high vacuum tubes.

Cathodes of the prior multi-cellular type, employed in tubes of moderate and large power size, may be divided roughly into two groups:

(1) The type having longitudinal vanes with one or more surrounding heat shields, open at one end to permit the egress of electrons. A cathode of this type is shown in Patent No. 1,924,318 issued jointly to W. A. Ruggles and me.

(2) The disk type of cathode which is also usually surrounded by one or more cylinders but is closed at each end and has openings about the periphery of the cylinder or cylinders for the discharge. A typical example of such a cathode is shown in Fig. 2 of my Patent No. 1,924,319.

While cathodes of both of these groups are satisfactory in operation, they are open to the objection, at least to some extent, that the current density throughout the cavities formed by the vanes or disks is not uniform. In the case of the vane type of cathode with openings at the end, i. e., nearer the anode, when the cathode and anode are mounted in coaxial alignment, it has been found that under some conditions practically all of the electron emission comes from only that portion of the cathode nearer to the anode. Very much less electron emission is obtained from the remote or deeper parts of the cathodal cavities, presumably due to the resistance offered to the flow of electrons by the long, narrow paths from the bottom of the cathode to the opening at the top, between the parallel walls of adjacent vanes. In the case of the disk cathode, most of the electron emission is produced under some conditions, at the outer or peripheral portions of the disks in spite of the fact that other portions are nearer the heater and therefore are at a higher temperature and for this reason should produce more electrons. The rea-

son that the disk cathode does not provide electrons evenly over its entire surface is believed to be due to the resistance of the narrow path between the parallel walls of adjacent disks. These points will be considered in detail when comparing the disk cathode with the improved vane cathode which forms the subject of the present invention.

Accordingly, the main object of the present invention is to provide a cathode which is not open to these objections, and in particular, a structure which has a uniform temperature over its entire active surface and a uniform arc current density throughout the cathodal cavities. Another object is to provide a cathode in which the electric field tending to pull electrons from the surface is substantially uniform throughout the cathode, while still further objects are to provide an indirectly heated cathode which offers a relatively large electron emission surface per unit volume of structure, and which is easy to fabricate and assemble, and also may be readily coated with electron-emitting material. In carrying out these objects, my invention contemplates, in brief, the use of a vane type of cathode surrounded by one or more cylinders which may serve as heat shields and in which the electrons leave the cathode in a radial direction, rather than from the end of the cathode nearer the anode. The ends of the cathode may be terminated by disks of solid, i. e. non-apertured, material which readily lend themselves to form a frame for supporting the vanes. The invention will be better understood when reference is made to the following description and the accompanying drawing in which Fig. 1 is an elevational view, partly broken away, showing a tube which contains a cathode improved in accordance with the present invention; Fig. 2 is an enlarged view of a partly assembled cathode; Fig. 3 is a plan view, partly in section, of the cathode; Fig. 4 is a partly exploded view of the cathode, showing the manner of assembly; Fig. 5 is another assembly view showing the manner in which the vanes fit together; Fig. 6 is an enlarged sectional view taken along line 6—6 in Fig. 2 and looking in the direction of the arrows; and Fig. 7 is a graph depicting the temperature changes over the length of the improved cathode as compared with those over a typical prior art cathode.

The device shown in Fig. 1 is illustrative of the type of devices to which my invention is applicable. It comprises a sealed envelope 1, preferably of a bulbous configuration, and closed at the respective ends by the usual reentrant stems 2, 3. There is a leading-in conductor 4 sealed

in the stem 2 and which supports a cylindrical anode of carbon or metal 5. A cathode 6 of the improved type, which will be described in detail hereinafter, is arranged preferably in coaxial alignment with the anode 5 and supported from a reduced diameter portion 7 of the stem 3 by means of a screw clamp 8 of ordinary design. Support rods 9 are secured to the clamp at one end and welded or otherwise secured to the cathode 6 at the other end. In addition to the anode and cathode, the envelope 1 may contain a grid structure 10 formed by a mesh cylinder which surrounds the electrodes and is held in position preferably by rods 11 which are welded or otherwise secured to a screw clamp 12 embracing the stem 3. Two conductors 13 are taken from the cathode 6 to the exterior of the tube, and a lead 14 is similarly connected to the clamp 12 so that control potentials may be applied to the grid 10. A cap 15 may be secured to the cathode conductor end of the envelope, and the various conductors taken through the cap in any suitable manner.

After the envelope 1 has been evacuated, an inert gas or a vapor-producing material is introduced so that when proper potentials are applied to the various electrodes, an arc or glow discharge is formed between the cathode and anode. Inasmuch as the invention is directed more especially to the cathode of such a device, it is believed unnecessary to describe the tube as a whole in greater detail because devices of this character are well known in the art.

The improved cathode, as shown more clearly in Figs. 2 and 4, consists of a radiation heated member surrounded by a large number of equidistantly spaced vanes which may, if desired, be coated with electron-emitting material 25, as indicated in Fig. 6. A heater coil 16 of tungsten or the like is wound on an alumina rod 17 which has an axial bore for receiving a conductor 18 which may serve as a return wire for the heater. However, the return circuit for the heater is usually taken from the cathode so that the wire 18 serves simply as a support. At each end of the alumina rod, there is a metal disk 19, the upper one as shown in Figs. 2 and 4, carrying a metallic cylindrical member 20 to which the adjacent ends of the conductors 16 and 18 are secured. Between the disks 19, a large number of vanes or strips 21 of metal are equidistantly spaced and secured in any suitable manner to the disks. A convenient way of securing the vanes to the disks is to provide the vanes with V-shaped extensions or tabs 22, as seen more clearly in Fig. 4, and bending these extensions at right angles to the vane, so as to provide a flat surface for welding to the disks at the places indicated by the small cross-hatched circles 23 shown in Fig. 3.

Whereas in the case of the prior art vane type of cathode, for example, that shown in Patent No. 1,924,318 referred to hereinbefore, the inner or radial edge of the vanes was secured, as by welding, to a metal cylinder which surrounded the heater, this separate cylinder may be entirely dispensed with and the vanes formed and assembled in such a manner that the cylinder is constituted of the vanes themselves. As shown more clearly in Figs. 4 and 5, this is accomplished by providing the vanes at their inner edges with a longitudinally extending extension 24 which, when formed and bent to the proper angle, may be arranged to overlap one another so that when completely assembled, they constitute a closed cylinder of the proper diameter efficiently to re-

ceive heat from the heater coil 16. While various ways will occur to those skilled in the art for assembling a cathode of this character, it has been found that the most satisfactory way involves the use of a demountable mandrel (not shown) which holds the two disks 19 in position while the vanes are being assembled and welded to the disks. Wooden wedges (not shown) may be employed to space the vanes apart and to maintain their proper position during the welding operation. After the vanes have been secured to the disks, the mandrel is taken apart. The feature of providing the vanes with the arcuate extensions 24 and the flat tabs 22, also the feature of using a collapsible mandrel for assembling and mounting the vanes, as described hereinbefore, are disclosed and claimed in U. S. Patent 2,154,298, issued April 11, 1939, in the name of Raymond B. Ayer, and entitled "Cathodes for electron discharge devices and methods of fabrication". It is apparent that when the vanes are constructed and assembled in the manner described, they may be made on a quantity production basis, rolled and cut to size and formed from strip material. The vanes may be coated with electron-emitting material 25 (see Fig. 6) before being assembled, as the subsequent welding operation is not such as detrimentally to affect the coating, or if desired, may be coated after assembly.

The lower disk 19 has three equidistantly spaced apertures which receive the support rods 9 referred to hereinbefore. These rods may have their upper ends bent at right angles in order more securely to be attached to the disk.

The operation of an improved cathode of this sort is well known in the art and little or no explanation appears necessary. The heater coil radiates heat to the cylinder formed by the overlapping vane extensions, and this heat is conducted to the vanes due to the integral metal connection and when the vanes reach a suitable temperature, electrons are emitted and flow toward the anode 5, after being electrostatically controlled by the grid 10. In the case of a gas or vapor device and when the applied potentials exceed the ionization voltages, a glow or arc discharge is produced in the tube, causing the production of positive ions which travel toward the cathode. It will be noted that the direction of travel of the electrons and positive ions is radial with respect to the cathode cylinder. There is no end emission because the disks 19 contain no discharge openings.

In order to reduce the thermal losses of the cathode, thereby minimizing the energy required to maintain the electron-emitting surfaces at the proper operating temperature, one or more heat shields 27 may be provided, the innermost shield being secured to the disks 19 or to the vanes 21 or both in such a manner as to reduce as far as possible heat conduction at the joints. These heat shields, as shown more clearly in Fig. 1, have a number of apertures 28, arranged in either a staggered or linear relation, but extending only over the periphery of the heat shields. An outer cap 29 may also be provided at each end of the outermost heat shield to add to the rigidity of the structure and prevent radiation of heat at the ends of the cathode. It will be noted that the apertures 28 are in a position substantially co-extensive with, or comparable to, the distance over which the vanes are presented to the interior surface of the heat shield or shields so as to permit egress of the electrons produced by the active sur-

faces of the vanes 21. The electrons, and in the case of a gas or vapor tube, also the positive ions leave or enter the cathode in a radial direction.

A vane cathode of the type described and having radial or side electron emission offers certain advantages over prior vane cathodes which have end emission, such as for example that shown in Patent No. 1,924,318 referred to hereinbefore. In the case of the radial emitter, which forms the subject of the present invention, the depth of the cathodal cavity is equal approximately to the width of the vane. This is obviously of much less dimension than the depth of the cathodal cavity of the end emitting vane cathode because in the latter case, the cathodal depth is approximately equal to the length of the vane. Assuming that the intensity of the anode field at the outer edge of the cathode is the same for both types of cathode, it is apparent that this field would effectively reach into only those cavities which are of shallow depth, such as are provided by the radial emitter vane cathode. Consequently, the voltage drop which causes the electrons to leave the surfaces of these inner recesses is greater than in the case of the end emitter vane cathode.

The radial emitter vane cathode, which forms the subject of the present invention, also offers many advantages over the radial emitter disk cathode. In the first place, the vanes permit ready conduction of heat throughout the length of the cathode, thus causing the various surfaces to operate at a uniform temperature. In the disk cathode, there is little or no opportunity for the heat to flow from one disk to another except through the inner cylinder to which the disks are secured. The transfer of heat from the outer portion of one disk to that of the next is practically limited to radiation. Consequently, the temperature of all parts of the disk cathode is not uniform but is subject to considerable variation, which condition is not conducive to high efficiency of operation. Moreover, in the improved vane cathode the resistance to heat flow from the center to the periphery is much smaller than in the disk type, so that there is less difference in temperature between portions near the center and at the periphery.

The non-uniformity of temperature throughout the disk cathode is illustratively exemplified in Fig. 7 of the drawing which graphically depicts the temperature variations throughout the length of a disk cathode compared to those of the improved vane cathode. In this figure, the ordinates are in degrees centigrade temperature and the abscissae are divided into four parts to indicate the condition at certain distances parallel to the axis of the respective cathodes which in the case of a cathode having a heat shield with five apertures, would represent the condition at the various openings in the heat shield. The full lines represent the temperature variations of the improved vane cathode, while the broken lines represent similar variations of the disk cathode. Taking a few values, for example, the middle set of curves which have been designated X and Y respectively and represent normal operating values, it will be noted that the curve X is almost a straight line and nearly flat except for a slight dip between the last opening and the bottom of the cathode. This particular curve shows that at the top or first opening of the vane cathode, the temperature was approximately 875° C. and at the second opening in the heat shield, or one-fourth of the distance down the cathode, the temperature had dropped only a few

degrees, and at the third and fourth openings which would represent one-half way down and three-fourths way down the cathode respectively, the temperature was approximately the same as at the second opening in the heat shield. The most extreme difference in temperature appeared at the bottom of the cathode and at this point, the temperature was approximately 860° C., leaving a temperature difference of only 15° C. from top to bottom. Examining the broken line curve Y, which depicts the temperature conditions throughout the length of a disk cathode, we find that the top of the cathode, at the first opening, is approximately 835° C. and at the second opening, the temperature has risen to 880° C.; while one-half way down, the temperature had gone still higher—to 910° C. and had then dropped very abruptly so that at the fourth opening, the temperature was approximately 875° C., while the bottom, at the last opening of the cathode, was considerably less than 800° C. Consequently, from the top to the middle of the cathode there was an increase in temperature of approximately 75° C. and between the middle of the cathode and the bottom there was a drop of more than 100° C. It will also be noted in Fig. 7 that these extreme variations of temperature are present in the disk cathode even when the temperature of the cathode is raised or lowered. In all cases, the temperature curves for the vane cathode are much more nearly straight than the disk cathode, indicating that the temperature throughout the vane cathode is more nearly uniform.

In addition to providing an advantage by way of greater uniformity of temperature, and therefore uniformity of electron emission, the vane cathode having radial or side emission offers, in the case of a gas or vapor tube, the distinct advantage of providing a more uniform arc current density throughout the various recesses or cavities, due to the fact that the width of the cavities increases uniformly in going from the center to the outside. Consequently, in this type of cathode, all parts of the entire surface contribute electrons evenly to the arc current.

The advantage of the radial or side emission vane cathode over the disk cathode in regard to greater uniformity of arc current density may be expressed mathematically as follows: Taking up first the prior art disk cathode, let r equal the radius of each disk and h the distance between disks. If I is the electron current per unit area from the disks, the total electron current produced by the opposed sides of two adjacent disks is the area of each disk times I which is equal to $2\pi r^2 I$. This electron current has to leave the outer periphery of the two disks through an area of cylindrical configuration and having a length equal to the diameter of the disks and a width equal to the distance between disks. This area is equal to $2\pi rh$. The current density at the periphery of the disks is therefore equal to

$$\frac{2\pi r^2 I}{2\pi rh} = \frac{I}{h}$$

It will be noted that the current density factor includes the symbol " r ", showing that in the case of the disk cathode, the current density varies with the radius or diameter of the disks.

On the other hand, in the case of the vane type of cathode, it will be shown that the current density does not depend on the diametral size of the cathode, and hence, is substantially uniform at any diametral position in the cathode. Let r equal the radius of the cathode, i. e., the width of

each vane, and H the distance between disks 19 at the top and bottom of the cathode, which is equivalent to the length of each vane. Now let the angle between adjacent vanes be θ , and I the electron current per unit area of the cathode surface.

The total electron current produced by the opposed surfaces of two adjacent vanes, i. e., a segment of the cathode, is $2rHI$. This current has 10 to flow through an area at the boundary of the cathode which is equal to $2r \times \sin \frac{1}{2}\theta H$. The current density is therefore,

$$\frac{2rHI}{2r \times \sin \frac{1}{2}\theta H} = \frac{I}{\sin \frac{1}{2}\theta}$$

15 It will be noted that the current density expressed immediately above contains no factor relating to "r" because the "r" in the numerator of the fraction is canceled by the "r" in the denominator. Consequently, assuming uniform emission from the entire area of the vane, the current density is not related at all to the diameter of the vane cathode but is constant at any and all diametral positions in the cathode. As the vane emitting area is increased by going farther from the center, 20 the cross-sectional area increases at a proportional rate and the current density remains constant. Inasmuch as the current density remains constant, the electric field tending to draw electrons from the electron-emitting surfaces also 25 tends to remain constant, so that the outer portions of the vanes do not contribute any more than their equal share of electrons to the arc or electron current. On account of this uniformity 30 of arc density, it follows that a vane cathode of this type has a longer operating life than the disk cathode.

The vane cathode also offers many practical advantages over the disk cathode by way of manufacture and assembly. For example, the 40 vanes may be readily cut from strip material and formed with the least amount of waste and due to their general rectangular configuration, may be readily coated with electron-emitting material. Indeed, if desired, a mesh may be welded 45 to each side of the vane in order to retain heavier coatings of active material.

What I claim is new and desire to secure by Letters Patent of the United States:

50 1. An electron-emitting electrode for an electron discharge device comprising an elongate enclosure containing a heater, longitudinal vanes secured to said enclosure forming side and end openings, and means including a closure for the end openings for preventing electrons from leaving the ends of said vanes whereby electrons are permitted to leave the electrode only through the side openings.

60 2. An electrode for an electron discharge device comprising an elongate enclosure containing a heater, longitudinal vanes secured to said enclosure and a second enclosure surrounding said vanes and having peripheral discharge openings which extend lengthwise of said enclosure over a distance comparable to the length of said vanes.

65 3. A cathode for an electron discharge device comprising a cylinder containing a heater, longitudinally extending vanes secured to said cylinder, and a cylindrical enclosure surrounding said vanes, said enclosure being provided with radial discharge openings presented substantially to the entire length of the vanes.

70 4. A cathode for an electron discharge device

comprising a cylinder, a heater therein, vanes mounted externally on said cylinder, a coating material having high electron emissivity on said vanes, and a heat conserving cylindrical enclosure surrounding said vanes and having radial 5 openings for the egress of electrons emitted by said material, said openings extending lengthwise of said enclosure over a distance comparable to the length of said vanes.

5. A cathode structure adapted for use with an 10 electrical discharge device comprising a cylinder, a member of refractory insulating material in said cylinder, a heater supported by said member, longitudinal vanes mounted upon the external surface of said cylinder and a second cylinder 15 surrounding said vanes, said second cylinder being provided throughout substantially its entire peripheral surface with discharge openings.

6. An electron discharge device comprising an envelope containing a plurality of electrodes including an anode presented entirely to the end 20 of a cylindrical cathode, said cathode being provided with longitudinal vanes and being completely enclosed except for radial discharge openings, which extend lengthwise of the cathode a 25 distance comparable to the length of said vanes.

7. An electron discharge device comprising an envelope containing a plurality of electrodes including an anode presented entirely to the end 30 of a cylindrical cathode, said cathode being provided with longitudinal vanes and having openings except at the end adjacent said anode, said openings extending substantially over the entire length of the cathode.

8. A cathode structure for an electron discharge device comprising a cylinder containing a heater, longitudinally extending vanes secured to said cylinder and adapted to emit electrons, a cylindrical enclosure surrounding said vanes, said enclosure being completely closed except for peripheral discharge openings which extend a distance along the enclosure comparable to the distance over which said vanes are presented to the interior surface of the enclosure whereby the electrons emitted by the entire length of each vane are permitted to pass through the enclosure in 35 radial directions.

9. An electron discharge device comprising an envelope, a charge of gas therein, a plurality of electrodes including a cathode, said cathode comprising an elongated heater and a plurality of elongated strips extending longitudinally in said cathode outwardly from said heater, the elongated spaces between the outer edges of said strips being open, a material of high electron-emissivity coating said strips, and a shield surrounding said strips, said shield having openings which are spaced over substantially the length of the spaces between the outer edges of said strips.

10. A thermionic cathode structure adapted for 60 use in electrical discharge devices comprising an elongated resistance heater, a metal housing closely surrounding said heater, a plurality of elongated metal strips which are arranged with one longitudinal edge adjacent said heater, the spaces between the opposite edges of said strips being open, a material on said strips for enhancing electron emission, plates closing spaces between the ends of said strips and a surrounding heat shield having longitudinally arranged openings which are substantially co-extensive with the spaces between the outer edges of said strips.

ALBERT W. HULL.
